PRESS TIMER.

Application filed May 17, 1924. Serial No. 714,130.

This invention relates to presses and more particularly to improvements therein designed to control the duration of pressure imposed by a pressing machine; and while 5 I have chosen a conventional type garment presser with which to disclose the principle of my invention, it is to be understood how my press timer improvements may be used on other types of pressing and work treating machines.

Purpose.

Broadly speaking an object of my invention is to increase the efficiency of pressing machines, as for example hot jaw machines used in pressing and ironing the work; and the adoption of this invention renders it practical to increase the working temperature of the pressing members whereby the 15 work is more quickly dried and ironed; and such increased high temperature pressing jaws are not permitted to injure the work as by over heating for the reason that the timer mechanism constituting this invention 20 cuts short the pressure and contact period by causing the press to automatically open at a time predetermined as most efficient for work of a given character. Since this improved machine is capable of safely applying greater heat to the garment, it follows that the work is pressed more rapidly 25 and the production of the machine is increased.

In some cases it may be undesirable to 30 raise the temperature of the pressing members and in such event this press timer has its most important uses in that the human element and guess work are removed because an operator using present day machines may 35 himself open the press too soon one time and leave it closed longer than really necessary the next time thereby not working his machine to the best advantage and what is more failing to produce uniform work. In 40 this connection the timer is set to open at exactly the desired elapsed pressing period so no time is lost in over pressing and the quality of the work is not lowered due to 45 under pressing.

In addition to the above it may be said 50 that another object is to produce press timer control means highly adapted to garment presses and laundry ironers; and further-

more my improved machine incorporates the timer element as a unitary structure therewith and not as a separate unit. Besides this improvement and distinction, my press timer is itself driven by the press operating mechanism, as by an electric motor used to produce final pressure, and so separate driving means is not necessary for the press driving means is used to drive my power timed tripping mechanism.

Drawings.

The accompanying drawings illustrate the principle, and in many instances the construction, of my invention. Some parts thereof are shown diagrammatically and some parts necessary in commercial machines are omitted for clearness in disclosure. Changes in construction and mode of operation may be made without departing from the scope of the invention.

Figure 1 shows a front view of a pressing machine embodying the improved features constituting the invention; and Figure 2 shows a side view thereof.

Figure 3 illustrates a plan view in the form of a section removing the upper portion of the press to expose the parts constituting the invention.

Figure 4 shows a perspective view of the power drive mechanism employed to produce high pressure in the press as well as to drive the press timer and power tripping mechanism.

Figure 5 is a diagram of a multi-stage gear reduction transmission by which high speed rotation of a power means, as for example an electric motor, is reduced to a practically low speed rectilinear motion for operating a graduated trip or release bar.

Synopsis of the invention.

In high power pressing machines it is invariably the practice to employ motor means, as for example an electric motor, for producing final pressure and the pressing machine may be closed manually by the operator or may be closed by power depending upon the particular type of machine at hand. In the present instance I have chosen a power press of the motor driven type adapted to be closed by hand and the final pressure imposed by motor, and a continu-

ously running motor is employed which conveniently provides a driving means for the timer and automatic press opening device constituting the principal feature of this 5 invention.

A synopsis of the invention will be given and reference is made to Figure 5 for the purpose of explaining how the continuously running motor means is employed to slowly 10 drive a graduated trip member employed to operate a clutch, a switch, or any other suitable appliance by which the press is caused to automatically open. A main drive shaft 10 is continuously driven by the motor 15 means and carries a worm pinion 11 meshing with a worm wheel 12 which is fixed to and drives a spur gear 13 meshing with a large gear 14. The result of this gear train, of one, two, three or more reductions, is to 20 very slowly drive the final spur gear 65. A gear rack 16 meshes with the last driven gear 65 and travels vertically or horizontally, as the case may be. The gear rack is provided with a ratchet bar 17 carrying a 25 slider 18 which travels with this trip member 16—17. Slider 18 is provided with a spring pressed releasable dog 19 whereby it is adjustably fixed to the ratchet teeth of the bar and since the bar 17 is graduated, this 30 slider may be set in predetermined indicated position on the trip member and caused to impinge a lever arm 20 to oscillate the shaft 21 at the lapse of a short or long period of time depending whether the slider 18 is set 35 toward the front end as at "15" or the rear end as at "60" on the graduated bar. For example should the trip member or slider 18 be set near the top of the bar as at "15", it will reach engagement with the control lever 40 20 much earlier and thereby cause a much shorter pressing duration than when the trip member is placed for example at the lower end of the bar. It is to be understood that the shaft 21 is subjected to partial rotation 45 when the trip member 18 is forcibly driven thereagainst to cause the press opening mechanism, described elsewhere, to function; and the arm 20 may be employed to open an electric switch to stop a motor, or actuate 50 a clutch to disconnect rotating parts.

Having given in brief a plan of the invention, a typical pressing machine will now be described; thereafter an explanation will be given as to how the press timing and 55 automatic opening device is combined with the press to take the opening function of the pressing machine out of the hands of the operator to improve the character of the work and speed the output.

60 *A typical garment press.*

A press frame 24 supports a press buck 25 and a head 26 raises and lowers in relation to the buck to produce pressure on the 65 work between the pressing members or jaws.

A press lever or yoke 27 is pivotally mounted at 28 on the frame 24. The rear end of the press lever is provided with a swing link 29 which is pivotally connected to the lever as at 30. The lower end of the link 29 70 is provided with pin 31 disposed in the bottom end of a slot 32 made in the upper extremity of a support link 33 which is itself pivotally connected at 34 to a power lever 39 fulcrumed on the frame as at 37. 75

An overbalancing arm or swing link 35 has its upper end pivotally connected at 36 with the link 29 and its lower end pivoted in the frame at 37. The link 35 leans against, so to speak, the connected links 29 80 and 33 and the heavy weight of the link 35 imposes an overbalancing factor against the straightened links 29 and 33 to such an extent that said links 29 and 33 are caused to move outwardly when the operator removes 85 his hand from a press closing handle 38 provided for manually closing the press. The slot 32 permits the weight of the link 35 to move the pin 31 outwardly to the top of the slot 32 by the time the link 33 has folded 90 down into a horizontal position to cause the press head 26 to open high above the buck under the influence of a counterbalance weight 48. When the front end of the power lever is thrust downwardly by power 95 means to be hereinafter described the straightened links 29 and 33 thrust upwardly under great force and thus impose high compression between the pressing jaws 25 and 26. 100

Any suitable motor means for forcibly operating the power lever 39 may be employed and in the present instance there is shown an electric motor 41 driving through a fly wheel 42 and continuously rotating a 105 main drive shaft 10, which has a worm wheel 43 fixed on the shaft and meshing with a worm wheel 44 carried in a gear housing 45. The motor continuously drives the worm wheel 44 which is freely journaled on a cam 110 shaft 46 on the outer end of which is anchored a cam 47 engaging the aforesaid power lever 39. The power lever 39 has an up and down throw equivalent to the throw of the cam and the cam is driven downwardly and stops to hold the press under high compression and thereafter rotates 180 degrees to its uppermost position to permit the rear end of the lever 39 to drop downwardly with its pin 34 loosening up and removing compression from the pressing members to such an extent that the link 35 overbalances the straightened condition of the links 29 and 33 thereby causing them to move outwardly to permit the head 26 to lift 115 high above the buck. Any suitable form of periodic driving means may be employed to rotate the cam 47 to its two extreme positions, up and down, and stop the cam at each point for it is understood how a pressing 120 125 130

machine is left under pressure for a short duration of time; and in my invention the time is mechanically controlled by the machine itself as will be seen. A spring 40 normally holds the front end of the power lever 39 up.

In some instances a stop and start motor may be employed whereupon a switch is necessary for making and breaking the circuit supplying current to the motor, and my invention contemplates the use of either a continuously running motor or a stop and start motor. In the present application I have illustrated a continuously running motor as aforesaid and therefore have incorporated a stop and start clutch of any approved design whereby the motor is permitted to run continuously and the clutch is caused to automatically start and stop the cam 47 when the press is to be opened and closed under high pressure. I have illustrated in Figure 1 one suitable form of clutch mechanism interposed between the periodically driven cam shaft 46 and continuously driven motor shaft 10 but it is understood how any other character of clutch may be used. The clutch illustrated may comprise a disc 49 slidably fixed on the cam shaft 46 and a hub 50 normally lies in contact with an arm 51 fixed on a shaft 52. A clutch control lever 53 is fixed to the shaft 52 and so arranged that the arm 51 is moved towards the hub 50 to engage the clutch when the lever 53 is swung outwardly. The disc 49 carries driving pins 54 which engages the continuously running wheel 44 to pick up the disc 49 and cam shaft 46 to cause rotation of the cam 47; and a spring and trip mechanism 55 acts to throw the disc 49 with the pins 54 outwardly thereby disengaging the clutch disc 49 from the continuously running worm wheel 44 to permit the cam shaft 46 and cam 47 to stop after they have been driven one-half revolution. A manual control means is provided at the front of the pressing machine for controlling the action of the lever 53 to impose the final pressure under the control of the operator, and such means consists of a handle 56 carried on a shaft 57 and a shaft is provided with a pendulum bob 58 which acts to hold the handle 56 in its normally upwardly limited position and therefore after the operator has thrust the handle downwardly, it automatically returns to the position shown in Figure 1 due to the weight of the bob member 58. The member 58 cooperates with the clutch lever 53 to cause engagement of the clutch to produce a half revolution of the cam 47 and to this end a dog 59 is pivoted in the bob and forcibly thrust against the upper end of the clutch lever 53 when the bob 58 swings outwardly under the influence of the manual downward movement of the handle 56, but the

dog 59 pivots upwardly and swings past the clutch lever 53 on the back return movement of the bob 58 and again comes to rest in the position shown in Figure 1 ready to actuate the clutch lever when the clutch is to be engaged for imposing or removing high pressure.

The foregoing description covers in general a motor driven high pressure pressing machine of one suitable type with which to combine my invention. A description will now be given of principles of timer mechanism employed to automatically operate the handle 56 and shaft 57 for engagement of the clutch to rotate the cam 47 to upward position to automatically open the press. By employing my invention, the operator engages the clutch for the purpose only of imposing pressure and thereafter the press timer operates the shaft 57 to engage the clutch to cause the cam 47 to move upwardly to remove high pressure. Therefore the operator and press timer take time about, so to speak, in engaging the clutch.

The press timer mechanism.

The timer mechanism supplies a means for automatically engaging the clutch mechanism at a predetermined time whereby the press is caused to automatically open and the mechanism necessarily requires driving means which is supplied from the main drive shaft 10 as aforesaid, and to this end the worm 11 is fixed on the main drive shaft 10 and continuously drives a gear 12, or train embodying several stages of gear reductions, for the purpose of producing a substantially slow motion at the end of the train as hereinbefore described in the synopsis of the invention but for the purpose of illustrating the principles involved without complicating the disclosure with unnecessary parts, as by duplication of gears, I have diagrammatically illustrated the principal features of the timer in Figure 4 where one gear 12 takes the place of a multi-stage gear train reduction seen in Figure 5; and this gear 12 for all practical purposes is sufficient for an understanding of the invention. However, reference is made to Figure 5 for illustrating the engineering principles involved, for those skilled in the art will appreciate that a single gear reduction as shown in Figure 4 is not sufficient for producing the required slow motion trip action.

A commercial machine manufactured in accordance with the principles of my invention requires a multi-stage gear reduction set by which the high speed rotary means is resolved to a very substantially slow speed motion, and these parts are all incorporated within a comparatively small size gear housing but the housing is dispensed with in describing my invention in order to expose the parts for examination.

The continuously running power shaft 10 continuously drives the gear 12, or gear train 12-14, to very slowly rotate a shaft 61. One end of the shaft 61 is shown as being splined 6 as at 62 and a clutch member 63 is confined on the splined end to slide back and forth and engage a clutch part 64 which is made integral with a spur gear 65 freely journaled on the shaft 61 and not subject to being driven by the said shaft 61-62 until such time as the said clutch 63-64 is thrown into engagement by means hereinafter described. The spur gear 65 remains stationary during the continuous rotation of the 10 gear 12, shaft 61, and clutch member 63 during the time the head 26 and front end of the power lever 39 is up under the influence of the spring 40.

Automatic means are provided for shifting 20 the clutch member 63 back and forth on the splined end 62 of the continuously running shaft 61 for stopping and starting the spur gear 65, for it is this small slow speed spur gear 65 which is employed to 25 drive a graduated trip member employed to automatically open the press at the end of the fixed and predetermined pressing period.

A clutch fork 67 is made a part of a lever 68 which is pivoted at 69 to some suitable 30 part of the pressing machine frame 24; and the rear end of this lever 68 may be made with a slot 70 in which the upper end 71 of a timer control lever 72 is designed to slide back and forth to pivot the lever 68 about 35 its fulcrum point 69 to engage the clutch 63-64 and disengage it automatically under the control of the combined motor means and timer mechanism. The lower end of the lever 72 is provided with a slot 73 which is 40 confined on a pin 74 anchored to the lower lever already described. The lever 72 is fulcrumed as at 75 upon some suitable fixed part or bracket of the machine frame 24.

It is to be noted how an up and down motion 45 of the power lever 39 swings the timer control lever 72 about its fulcrum point 75 for similarly swinging the clutch fork 67 in and out to engage the two clutch member 63 and 64. When the power lever 39 goes 50 down under the influence of the cam 47, the clutch 63-64 is engaged thereby causing the spur gear 65 to start rotation and it continues to be driven in fixed engagement with the gear 12, or gear train 12-14, until an 55 upward travel of the cam 47 permits the power lever 39 to rise whereupon the two levers 72 and 68 undergo a reverse movement to that already described thereby disengaging the clutch 63-64, causing the said spur 60 gear 65 to cease revolving.

The gear rack, or other suitable slow movement part, is held in engagement with the periodically driven spur gear 65 by any suitable guide means designed to confine a 65 gear rack in operative position as will be

understood by those conversant with the art, but such guide is omitted from the present disclosure to clarify the illustrations and description. The timed tripping bar 16, when mounted in horizontal position, as in Figure 70 4, is provided with a spring 76 or other suitable means for returning it to its normally inactive position after it has performed the function of engaging the clutch to initiate the press opening movement. However, 75 when the timed trip bar is mounted in a vertical plane, as in Figure 5, it returns to its lowermost normally inactive position by its own weight.

A control lever 20 is pivoted on the frame 80 24 and has an arm 77 projecting through a slot 78 made in a control arm 79 anchored to the motor clutch control shaft 57 already described. Motion of the arm 20 oscillates the shaft 57. 85

Complete operation.

It is now understood how a mechanically operated arm 79 is anchored to the motor clutch control shaft 57 to oscillate that shaft 90 by power means for the purpose of working the clutch lever 53. The shaft 57 is oscillated one time by the operator to produce final pressure and the next time by the machine to release final pressure. 95

The work is spread upon the press buck and the operator pulls the head 26 down by the handle 38 which causes the links 29 and 33 to straighten up into the position shown in Figure 2. The operator holds the head 100 26 down by one hand and quickly thrusts the main control handle 56 down with the other hand which engages the motor clutch 44-49 thereby causing the cam 47 to move downwardly with great force upon the lever 105 39 to impose high compression between the press jaws.

When the power lever 39 goes down, the pin 74 carried thereby swings the lever 72 which in turn swings the clutch fork lever 110 67 to engage the timer clutch 63-64 which picks up the spur gear 65 and sets the timer in operation by imparting movement to the gear rack 16 driving its adjustable slider member 18 straight ahead toward the press opening trip lever arm 20; and it is noted that the motor 41 continues to run while the press stands still under pressure. When the trip slide 18 reaches and impinges the arm 20 there follows an oscillating motion 115 of the shaft 57 to again engage the power clutch 44-49 which causes a 180 degree upward movement of the cam 47 permitting the power lever 39 to travel upwardly under the tension of the spring 40 which again 120 swings the timer control lever 72 to disengage the clutch 63-64 thereby disconnecting the spur gear 65 from the gear 12, or from the gear train 12-14, the result of which is to permit the spring 76 to quickly return 125 130

the trip bar 16 rearwardly to its normal inactive position awaiting the next cycle of operation.

What I claim is:—

5. 1. A pressing machine comprising in combination, cooperating pressing members between which the work is treated, means for closing the press, motor means to produce high compression between the pressing members, mechanism causing the press to remain at rest under pressure while permitting the motor to continue in operation, a press opening means, a connection established between the mechanism and the press opening means 10 70
- 15 whereby the press opening means is set in operation when the press goes under high compression, a graduated member driven by the motor means after the press closes, adjustable means on the graduated member to 20 actuate the press opening means, whereby the press is caused to automatically open at any selected predetermined time, and means cooperating with the graduated member for initiating the operation of the press opening 25 means. 80
2. A pressing machine comprising in combination, relatively movable pressing members, manual press closing means carried with one member, motor power final pressure 30 creating means, a manual control lever to start the final pressure means, a mechanical means for actuating the manual control lever, and mechanism forming part of the motor means to operate the mechanical means for 35 the purpose of automatically opening the press at the end of an elapsed pressing period. 90
3. A pressing machine comprising in combination, relatively movable pressing members, manual press closing means, motor power final pressure creating means, a manual control lever to start the final pressure means, a mechanical means connected with the motor for actuating the manual control 40 95
- 45 lever, mechanism forming part of the motor means to operate the mechanical means for the purpose of automatically opening the press at the end of an elapsed pressing period, means permitting the control lever to 50 be operated by the operator independently of the mechanical actuating means, and means permitting the said mechanical means to be operated independently of the manual control lever. 100
- 55 4. A garment pressing machine comprising in combination, pressing members between which the work is treated, operating means connected with a member to close the press, motor means connecting with the operating means to produce compression, a timer control lever connected with and actuated by the motor means, a clutch driven by the motor means and actuated by the timer lever, a driver member operated by the clutch, a trip bar operated by the driver 60 110
- member, an adjustable trip carried on the bar, a second lever free of but operable by the trip and bar, and means actuated by the last named lever to open the press. 115
5. A garment pressing machine comprising in combination, pressing members between which the work is treated, closing means therefor, a power unit including means connecting it with the pressing members by which compression is produced in the work, a power clutch connected with the power unit by which the power unit is connected and disconnected with the pressing members to impose and remove compression, an automatic trip means operatively connected with the power unit to open the press, a timer clutch connected with the power unit to set the trip means in operation, a trip bar forming part of the trip means and caused to travel forward to actuate the trip means to open the press after elapsed time when the timer clutch is engaged. 120
6. A garment pressing machine comprising in combination, pressing members between which the work is treated, closing means therefor, a power unit including means connecting it with the pressing member by which compression is produced in the work, a power clutch connected with the power unit by which the power unit is connected to and disconnected from the pressing members to impose and remove compression, an automatic trip means to open the press, a timer clutch connected with the power unit to set the trip means in operation, a trip bar forming part of the trip means and caused to travel forward to actuate the trip means to open the press after elapsed time when the timer clutch is engaged, and means causing the trip means to return to normal position 105 130
7. A pressing machine comprising in combination, cooperating pressing members between which the work is treated, press closing means, a power unit connected with the pressing members delivering high pressure onto the work, a power clutch operatively connected with the power unit for starting and stopping the high pressure period, a manual control lever connected with the clutch to engage the power clutch, a mechanically operated element connected with the clutch to engage the power clutch alternately with the manual control lever, the arrangement being such that the operator only engages the clutch every other time it functions, and a timer unit connected with the power unit to automatically operate the element to engage the clutch to open the press. 125
8. A pressing machine comprising in combination, cooperating pressing members between which the work is treated, press closing means, a power unit connected with the power unit delivering high pressure onto the work, a power clutch connected with the 130

power unit for starting and stopping the high pressure period, a manual control lever connected with the clutch to engage the power clutch, a mechanically operated element connected with the clutch to engage the power clutch alternately with the manual control lever, the arrangement being such that the operator only engages the clutch every other time it functions, a gear reduction connected with and driven by the power unit and designed to have the final gear thereof slowly revolved, and means driven by the slowly revolving final gear to operate the element to engage the clutch alternately by power as aforesaid.

9. A pressing machine comprising in combination, cooperating pressing members between which the work is treated, press closing means, a power unit connected with the 20 pressing members delivering high pressure onto the work, a power clutch connected with the power unit for starting and stopping the high pressure period, a manual control lever connected with the clutch to engage the power clutch, a mechanically operated element connected with the clutch to engage the power clutch alternately with the manual control lever, the arrangement being such that the operator only engages the 25 clutch every other time it functions, a gear reduction driven by the power unit and designed to have the final gear thereof slowly revolved, a graduated trip gear rack driven by the final gear, and adjustable means movable on the rack adapted to be set to actuate the mechanically actuated element.

10. A pressing machine comprising in combination, cooperating pressing members between which the work is treated, press 40 closing means, motor means connected with the pressing members, a power clutch operatively connected with the motor means for starting and stopping the high pressure period, a manual control lever connected with the clutch to engage the power clutch, a mechanically operated element connected with the clutch to engage the power clutch alternately with the manual control lever, the arrangement being such that the operator 45 only engages the clutch every other time it functions, a gear reduction driven by the motor means to slowly revolve a final gear, a graduated trip gear rack driven by the final gear, adjustable means on the rack adapted 50 to be set to actuate the mechanically actuated element, a timer clutch connected with the press closing means by which the trip gear rack is set in motion, and means for returning the gear rack to normally inactive 55 position.

11. A pressing machine comprising in combination, cooperating pressing members between which the work is treated, press closing and motor means connected with the 60 pressing members, a power clutch connected

with the motor means, a manual control lever connected with the clutch to engage the power clutch, a mechanically operated element connected with the clutch to engage the power clutch alternately with the manual control lever, the arrangement being such that the operator only engages the clutch every other time it functions, a gear reduction driven by the motor means including a final gear slowly revolved, a graduated trip gear rack driven by the final gear, adjustable means movable on the rack adapted to be set for a predetermined time to actuate the mechanically actuated element, a timer clutch connected with the motor means by which the trip gear rack is set in motion, means for returning the gear rack to normally inactive position, and means for automatically disengaging the timer clutch at the end of the pressing period.

12. A pressing machine comprising in combination, cooperating pressing members, closing means therefor, a power transmission to produce final high pressure, a continuously running motor driving the transmission, a power clutch of the automatically disengaging type including means to connect and disconnect the transmission to and from the motor, a clutch lever arranged to engage the clutch, manual control means to permit the operator to work the clutch lever to cause the motor means to impose high pressure, power releasing means designed to similarly work the clutch lever but to release said final pressure independently of the operator, a multi-stage gear reduction set driven continuously by the motor and having a final gear thereof slowly operated, a gear driven trip member having delayed movement operated by the slow gear adapted to cooperate with the aforesaid power releasing means to work said clutch lever, and means arranged to automatically start the movement of the gear driven trip member at the instant the closing means functions.

13. A pressing machine comprising in combination, cooperating pressing members, closing means therefor, power means adapted to produce final high pressure, a continuously running motor driving the power means, a power clutch of the automatically disengaging type to connect and disconnect the power means to and from the motor, a clutch lever arranged to engage the clutch, manual control means designed to permit the machine operator to work the clutch lever to cause the motor means to impose high pressure, power releasing means designed to similarly work the clutch lever but to release said final pressure independently of the operator, a multi-stage gear reduction set driven continuously by the motor and having a final gear thereof slowly operated, a gear driven trip member having delayed movement operated by the slow gear

adapted to cooperate with the aforesaid power releasing means to work said clutch lever, means arranged to automatically start the movement of the gear driven trip member at the instant the closing means functions, and mechanism operative by opening of the press to automatically stop and return the trip member after it has worked the clutch lever.

10 14. A pressing machine comprising in combination, cooperating pressing members and closing means therefor, power means operatively connected with the pressing members adapted to produce final high pressure, a continuously running motor driving the power means, a power clutch of the automatically disengaging type interposed between motor and power means to connect and disconnect the power means to and from the motor, a clutch lever connected with the clutch, manual control means connected with the clutch, power releasing means connected with the clutch, a multi-stage gear reduction set driven continuously by the motor and having a final gear thereof slowly operated, a gear driven trip member having delayed movement operated by the slow gear to cooperate with the aforesaid power releasing means to automatically disengage 20 the clutch, a timer clutch connected with

the power means to start movement of the trip and stop movement thereof, and means operating in conjunction with the aforesaid press closing means to operate the timer clutch.

35 15. A timer for motor means operated presses including a manually operated jaw closing handle and including a manually operated lever to control the motor means and initiate a final pressure operation, comprising: a trip member, a slow motion drive to move the trip member to tripping position, and means, including a clutch, operated from the motor of the press to run the slow motion drive; a motion transmitting 40 means in line with and actuated by the trip member including means adapted to be connected with the manually operated lever of the press; and clutch control means connected with the clutch, and adapted to be 45 operatively connected with a moving part of the press including means to engage the clutch when the jaw closing handle is moved to close the press, and including means to disengage the clutch when the trip member 50 actuates the motion transmitting means.

55 In testimony whereof I affix my signature.

HART A. STODDARD.
